TEXTILE FABRIC

Nathan Miller, Lynbrook, N. Y., assignor to Cohn-Miller
Company, New York, N. Y., a partnership

Application November 9, 1953, Serial No. 27,487

Term of patent 3½ years

(Cl. D92—1)

To all whom it may concern:

Be it known that I, Nathan Miller, a citizen of the United States of America, and a resident of Lynbrook, New York, have invented a new, original, and ornamental Design for a Textile Fabric, of which the following is a specification, reference being had to the accompanying drawing, forming a part hereof.

The figure is a plan view of a textile fabric showing my new design.

I claim:

The ornamental design for a textile fabric, as shown.
